(57) CLAIM

The ornamental design for pencil cases, substantially as shown and described.

DESCRIPTION

FIG. 1 is a top, front and left side perspective view of a pencil cases, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an expanded view of the first layer of the pencil cases; and,

FIG. 9 is an expanded view of the second layer of the pencil cases.

The broken lines in the drawings illustrate portions of the pencil cases, which form no part of the claimed design.
